UNITED STATES PATENT OFFICE

2,607,083

TEXTILE FIBER DRAFTING FRAME

Whitworth F. Bird, Swarthmore, Pa., assignor to
 Collins & Aikman Corporation, Philadelphia,
 Pa., a corporation of Delaware

Application November 17, 1948, Serial No. 60,534

12 Claims. (Cl. 19—131)

1

This invention relates to textile fiber processing apparatus such as drafting frames which may be used in forming rovings, yarns and similar strands from fibers of wool, cotton, rayon, blends of the same either singly or in combination.

More particularly, it is directed to a draft frame having the usual front drawing off rollers, a horizontally adjustable driven roll and a top roll centered forwardly of the said adjustable driven roll. The frame may and preferably does contain a nose bar positioned close behind the nip of the drawing off rolls. An apron may or need not be used and when used passes over the nose bar, the driven roll and about a yieldingly mounted tensioning means. My improvements are useful, however, in all cases where substantial vertical and horizontal adjustment of the top roll is required so as to maintain a close relationship to the front rolls or the nose bar. It is to be noted that in the illustrated embodiments, the bottom driving roll, by being made adjustable horizontally, admits of maintaining both close positioning between the nose bar in all adjusted positions and considerable vertical adjustment. My improvements are highly desirable in this environment.

Difficulty has been experienced in providing a convenient and accurate adjustment means for the top roll. The cap bar inclined slot arrangement as shown, for example, in Butler Patent 1,444,658 or Shaw 2,233,963, tends to obscure the vision of the operator, requires more parts and is inconvenient for making either a great number of adjustments across the frame or accurate adjustment of substantial size.

Also a single plane surface guide operating in conjunction with an ordinary round or regular shaped shaft is unable to give the substantial and accurate adjustment required.

The center of the top roll must take an arcuate or curved path when it moves through its adjustment range. This is necessary to maintain a definite or predetermined spaced relation between the nose bar and top roll and to insure that the top roll will be as far forward as its particular vertical adjustment or the type of stock permits.

According to my improvements I provide a support which is fixed to the frame, or if adjustable, is seldom moved. Adjustment is made without resorting to the use of securing screws and the like. This support cooperates with the top roll shaft to cause it to follow an arcuate or curved path and thus maintain a predetermined spaced relationship with the nose bar or front nip in any particular adjusted position of the top roll. This

2

result is conveniently accomplished by the provision of an intermediate support for the top roll shaft which support is eccentric to the bearing center of the shaft or by curved supports with or without eccentricities as will be more fully explained.

As described in my prior United States Patent No. 2,471,057, granted May 24, 1949, the frames shown therein provide for adjustment of a slip draft roll in both a horizontal and vertical direction. The vertical adjustment may approximate from $\frac{1}{16}$ to $\frac{1}{8}$ inch for a slip roll having apron driving or spacing collars about $1\frac{1}{4}$ inches in diameter. These adjustments are much too great to be made by the nose bar as this would change the zone of fiber control rather than being a change in degree of control within the zone of close control.

An object of my invention is to provide a convenient adjustment for the top roll capable of substantial vertical and horizontal adjustment into positions along an arcuate or curved path.

Another object is to provide an adjusting means for a top roll of draft frames in which a horizontal adjustable driving bottom roll cooperates in several adjusted positions with said top roll to drive the top roll and/or an apron.

Another object is to provide an adjusting means, for a top roll of draft frames, including an eccentric which is conveniently a part of the normal operating parts.

These and other objects of invention will be manifest from a consideration of the following description, claims and drawings in which:

Fig. 1 is an elevational somewhat diagrammatic view of my draft frame showing an eccentrically mounted top roll shaft and the usually fixed support.

Fig. 2 is a detailed assembly showing the relation of parts and a central supporting arrangement for the shaft.

Fig. 3 is a modification in which the usually fixed support is curved.

Fig. 4 is another modification in which the eccentric is bodily pivotable to effect the several adjustments.

In Fig. 1 I show the general arrangement of two front drawing off rolls 10 and 11 which form the usual front drawing off nip, and a pair of back feeding rolls 12 and 13. Roll 13 is a stock supporting feed roll. The use of roll 12 is optional when the roll 19 is a ratch forming roll. Positioned between the pairs of rolls is a fiber control unit comprising a nose bar 14, apron 15, and horizontally adjustable driving roller 16 having a shaft 17 journaled on frame 18. A top roll 19

which may be a solid, shell or slip roll with rigid collars 20 (see Fig. 2) forms an apron driving nip with the roller 16 to drive the apron 15. A spring 21 or other weighting means may be used to increase the apron nip pressure if its own weight is insufficient. A yieldable mounted apron tensioning roll 22 pivots about 23 on frame member 18a.

The pair of top rolls is supported by a shaft 25. The shaft 25 is centrally supported, this being an old feature per se as illustrated by such patents as Stahlecker 2,246,474. I have found it highly desirable that the center of the top roll be positioned along an arcuate or curved path in its several adjusted positions in order to maintain a proper spaced relationship between the top portion of the nose bar and the periphery of the top roll. To accomplish this I provide the shaft 25 with matched eccentrics 26. The eccentrics 26 are preferably integral with the shaft, but not necessarily so. The rolls, such as roll 27 in Fig. 2 having protective collars 20 and slip draft portion 29 of pins or other material more fragile than the collars, turn freely on stationary shaft 25.

As will be seen from Fig. 1 the several facets 30 of polygon matched eccentrics 26 are differently spaced from the center of the shaft 25. The usually fixed support 32 is secured to the frame 18 as by bolt 33 and preferably has two inclined ledges to which the facets may be applied or slide on. It will be seen that adjustment of the frame may be accomplished as desired by positioning a pair of facets 30 on the support 32 so that the proper relationship between the nose bar and front rolls exists. The horizontally adjustable roller 16 is then moved up into apron nip forming position. By using the corresponding facets on the other side of the frame, the proper adjustment automatically results. It will be understood that my polygon may have 3, 4, 5 or more sides and their spacing from the center is correlated with the inclination of the support 32.

Fig. 3 shows a modification in which there is provided a usually fixed support 40 having an arcuate surface 41 concentric or slightly eccentric to a point within and close to the tip of the nose bar. If the nose bar forms a quadrant or semi-circle the centers may, but need not exactly coincide.

In this modification the shaft support block 42 has concave surfaces differently spaced from the center of the shaft 25'. The structure may result in less frequent or smaller changes of the facets than that of Fig. 1. When the curve generated by the center of the top roll is regular as in a section of a circle or ellipse this modification is quite convenient. A spring may, of course, be applied as shown in Fig. 1 and is omitted for clarity in Figs. 3 and 4 of the drawings. It will be understood that the short portions of the eccentric are not bearing portions, but merely connect the curves. More or less than 4 surfaces are contemplated.

Fig. 4 represents a third modification in which the eccentric member 50 may bodily pivot about a member 51 fixed to the frame 18''. A number of pivot points 52 are spaced from the center of the shaft 25'' when in operating position so as to provide about $\frac{1}{8}$ '' vertical changes over a $\frac{1}{8}$ '' adjustment range with a top roll approximately $1\frac{1}{4}$ inches in diameter. The pivot points may be identified according to the setting they will produce. As will be understood, the shape of the eccentric 50 will be to some extent controlled by

the position of the shaft center, and may be either circular, elliptical or the like. Preferably the eccentric should be comparatively large so as to give effective leverage for weighting means such as spring 21 as shown in Fig. 1.

However, in frames using a nose bar the matter of space is important and sometimes it is necessary to keep the size of the eccentric such that it does not greatly extend beyond the outline of the top or that it be completely confined within this outline.

From a consideration of the above, it will be seen that I have provided built-in adjustment structures for top rolls having substantial vertical and horizontal adjustment. Vertical and horizontal as used herein are being used in the sense of transverse and longitudinally of the path of the stock. The frames are frequently inclined.

It will also be seen that the most desirable setting may be obtained for the stock as well as for machine relationships. The shaft for the top roll need not rotate and the eccentrics are optionally separate or integral with the shaft 25. The eccentric and shaft proper is somewhat referred to herein as an eccentrically mounted shaft assembly and the curved path recited in the claims is intended to include irregular or smooth curves. A straight line adjustment for the adjusting range is not included nor is it adequate for my purposes.

In all the figures, the basic parts have been given the same numerals in the interest of brevity and the parts are functionally shown for simplicity. It will be noted, however, that the nose bars, 14, 14' and 14'' may vary somewhat in design. The eccentric supports are in all cases positioned laterally of the apron. This may be centrally of a pair of top rolls as in Fig. 2 or outside the rolls as will be understood.

Having described my invention in separate embodiments, but wishing to be limited only by the scope of the following, I claim:

1. In a drafting device for textile fibers a pair of front drawing off members, strand feeding means including a pair of back feed rolls, a horizontally adjustable bottom driving roll, a top roll centered forwardly of said bottom roll and in operative engagement therewith, a supporting shaft for the top roll, means for adjusting the horizontal and vertical position of said top roll relative to said front drawing off members in a plurality of positions along a curved path whereby the end of the supporting shaft defines a curved path in a vertical plane according to its adjustment movement, said adjusting means including a support mounted in a fixed position independent of the various adjustment positions of the horizontally adjustable bottom roll and positioned below the top roll shaft in supporting relationship thereto, said support having a surface disposed at an angle to the direction of adjustment of the bottom roll for supporting said top roll shaft.

2. The drafting device of claim 1 further characterized by the fact that the top roll shaft supports a pair of top rolls and that the shaft support is centrally positioned relative to said pair.

3. In a drafting device for textile fibers a pair of front drawing off members, strand supporting means including a pair of back feed rolls, intermediate fiber control means, a horizontally adjustable bottom driving roll, a nose bar, a top roll centered forwardly of said bottom roll and positioned in operative engagement therewith, a supporting shaft for the top roll, means for adjusting the horizontal and vertical position of said top roll

relative to said nose bar in a plurality of positions along a curved path whereby the end of the supporting shaft defines a curved path in a vertical plane in accordance with its adjusted movement, said adjusting means including a support mounted in a fixed position independent of the various adjustment positions of the horizontally adjustable bottom roll and positioned below the top roll in supporting relationship thereto and having a surface disposed at an angle to the direction of adjustment of the bottom roll for supporting said top roll shaft.

4. The drafting device of claim 3 further characterized by an eccentric attached to the top roll shaft, said eccentric having a plurality of surfaces adapted to selectively engage the said surface of the fixed support.

5. The drafting device of claim 4 further characterized by weighting means operatively connected to said top roll shaft.

6. The drafting device of claim 4 further characterized by the fact that the fixed support has a surface slide and that the eccentric has three or more sides differently spaced from the center of the top roll shaft any one of which sides may contact said surface slide.

7. The drafting device of claim 3 further characterized by a weighting means operatively connected to the top roll shaft.

8. The drafting device of claim 3 further characterized by the fact that the top roll shaft supports a pair of top rolls and that said shaft is centrally positioned with respect to said pair.

9. In a drafting device for textile fibers, a pair of front drawing off members, strand feeding means including a pair of back feeding rolls and an endless looped apron having a strand support portion, supporting means for the apron including a nose bar close behind the front drawing off members, an apron tensioning roll yieldingly positioned within the apron loop, a horizontally adjustable bottom driving roll mounted within the loop of said apron, a top roll centered forwardly of said bottom roll and positioned above said apron in nip forming relation with said apron and said bottom roll, a supporting shaft for the top roll, means for adjusting the horizontal and vertical position of said top roll supporting shaft relative to said nose bar in a plurality of positions above said apron along a curved path whereby the end of the supporting shaft defines a curved path in a vertical plane according to its adjustment movement, said adjusting means including a support mounted in a fixed

position independent of the various adjustment positions of the bottom roll and an eccentric attached to the top roll shaft, said eccentric having a plurality of operative surfaces adapted to selectively engage the fixed support.

- 5 10. In a drafting device for textile fibers, a pair of front drawing off members, strand feeding means including a pair of back feeding rolls and an endless looped apron having a strand supporting portion, supporting means for the apron including a nose bar close behind the front drawing off members, an apron tensioning roll yieldingly positioned within the apron loop, a horizontally adjustable bottom driving roll mounted within the loop of said apron, a top roll centered forwardly of said bottom roll and positioned above said apron in nip forming relation with said apron and said bottom roll, a supporting shaft for the top roll, means for adjusting the horizontal and vertical position of said top roll supporting shaft relative to said nose bar in a plurality of positions above said apron along a curved path whereby the end of the supporting shaft defines a curved path in a vertical plane according to its adjustment movement, said adjusting means including an arcuate support mounted in a fixed position independent of the various adjustment positions of the bottom roll and means integral with the top roll shaft adapted to slide over the arcuate support.
- 15 20 25 30 35 40 45 50

11. The drafting device of claim 10 further characterized by the fact that the top roll shaft supports a pair of rolls and that the arcuate support is centrally positioned relative to said pair.
12. The drafting device of claim 10 further characterized by the fact that the means integral with the top roll shaft is concave.
